UNITED STATES PATENT OFFICE.

GEORGE G. COCKBURN, OF CLEVELAND, OHIO, ASSIGNOR TO T. H. BROOKS
AND W. H. SHEPARD, OF SAME PLACE.

CORNER STREET-SIGN.

SPECIFICATION forming part of Letters Patent No. 602,427, dated April 19, 1898.

Application filed May 17, 1897. Serial No. 636,863. (No model.)

To all whom it may concern:

Be it known that I, GEORGE G. COCKBURN, a citizen of the United States, residing at Cleveland, in the county of Cuyahoga and 5 State of Ohio, have invented certain new and useful Improvements in Corner Street-Signs; and I do hereby declare the following to be a full, clear, and exact description of the invention, such as will enable others skilled in 10 the art to which it appertains to make and use the same.

The object of the invention is to provide a novel and effective construction for corner street-signs, whereby said signs, although 15 adapted to be secured to a corner-building, are especially adapted to be easily and quickly secured to a post, whatever be its size, within reasonable limits.

The invention consists of two sign-plates 20 hinged together at their ends, in combination with inwardly-bent legs, which are secured, respectively, to said plates, the said legs serving as the means for connecting said sign-plates to suitable supports.

25 It also consists in the more specific combination of parts, as shown, described, and pointed out in the claim.

In the drawings, Figure 1 is a perspective view of my improved corner-sign when attached to a supporting-post. Fig. 2 is a front elevation of one of the sign-plates. Fig. 3 is a sectional view on line 3 3 of Fig. 2, and Fig. 4 is a plan view of the sign when attached to a corner-building.

35 Referring to the parts by letters, A A' represent two sign-plates, each of which has the same lettering on both sides. These plates are hinged together at one end, the hinge-ears a' being formed integral with the 40 plates. The plates may therefore stand at right angles to each other or at an angle greater or less than a right angle. On the lower edge of each plate near its middle is a depending ear a², having in each side a recess 45 a³. A leg B is secured to each ear, its upper

end lying in said recess. These legs are of approximately ogee form, whereby their lower ends will be considerably nearer to each other than their upper ends and will be adapted to be secured to the sides of a corner-building 50 E, as shown in Fig. 4, or to a post D, as shown in Fig. 1. Whatever be the size of the post, within reasonable limits, the lower ends of the legs may be brought into contact with it, while the two plates stand at right angles, or 55 nearly so. A clamp C is employed to secure said legs to the post. This clamp may be a U-shaped clip c, which embraces the post and legs, a plate c', through which the ends of the clip pass, and nuts on the ends of the clip- 60 legs.

The described construction is adapted to be placed on any of the four corners of a street by swinging the plates on their hinge-pivot to bring their inner faces outermost 65 and by changing the legs from one side to the other of the ears a².

When the described sign is attached to a post, the lettering upon both sides of the plate will be visible and may be read. 70

Having described my invention, I claim—
A corner street-sign consisting of two sign-plates hinged together at their ends, and each plate lettered on both sides provided with an ear a² upon its lower edge, and which ear is 75 recessed upon both of its sides, combined with the bent legs B which have their upper ends so shaped as to fit in the recesses in the ear, and their lower ends bent to bear vertically 80 against a suitable support; and a clamp which surrounds the support and secures the lower ends of the legs rigidly thereto, substantially as shown and described.

In testimony whereof I affix my signature in presence of two witnesses.

GEORGE G. COCKBURN.
